UNITED STATES PATENT OFFICE.

WALDEMAR KOPS, OF NEW YORK, N. Y., ASSIGNOR TO KOPS BROS. INC., OF NEW YORK, N. Y., A CORPORATION OF NEW YORK.

APPAREL GARMENT.

Application filed January 31, 1928. Serial No. 250,793.

This invention relates to an apparel garment and more particularly to that type of garment which is constructed to include both a girdle and a brassière and is made 5 to have the parts attachable at the side so as to be thus secured on the body of the wearer. The particular object of the invention is the provision of a belt device arranged in the front of the garment at the 10 inner side thereof to flatten or otherwise control the diaphragm of the wearer. The garment is so constructed that this diaphragm belt or strap extends entirely across the front member of the garment and co- 15 operates with a centrally disposed liner member for exerting the necessary tension at the proper place to cause the garment to function in its intended manner, as will be hereinafter more particularly described.

20 In the drawing Figure 1 is a perspective view illustrating the use of a garment made in accordance with this invention.

Fig. 2 is an elevation on a larger scale also illustrating the garment, and

25 Fig. 3 is a plan showing the inner side of the garment when the same is in a flat position.

By reference to the drawing it will be seen that in carrying out the invention the 30 garment includes a front member in which there is a centrally disposed liner member to assist in supporting the abdomen, a back member, side members, and a diaphragm strap or belt extending across the front 35 member. The front member of the garment, as illustrated, includes a central section 10 and lateral sections 11 and 12. The front or central section 10 is connected to the section 11 by a reinforcing strip 13 and 40 suitable lines of stitching. In a similar manner the central section 10 of the front member is connected to the section 12 by a reinforcing strip 14 and suitable lines of stitching. These sections of the front member 45 extend from the upper to the lower edges of the garment and are of sufficient length to cover the body from a point or line above the bust to a point or line below the thighs.

50 The garment also includes a back member 15 as well as side members each of which, as illustrated, includes a section of inelastic material and a section of elastic material. In the right hand side member 55 the section of inelastic material is indicated

at 16, and the section of elastic material at 17, whereas in the left hand side member the section of inelastic material is indicated at 18 and the section of elastic material at 19. It will be understood that all of the 60 sections of the garment to which reference has been made are preferably of inelastic material with the exception of the sections 17 and 19 which, in addition to being made of suitable elastic material, are gore shaped 65 and adapted to diverge downwardly from points at approximately the waist line, or slightly below the same, to the lower edge of the garment. The back member 15 is connected to the sections 16 and 17 of the 70 right hand side member by a reinforcing strip 20 and suitable lines of stitching, while the sections of this right hand side member are connected to each other by a reinforcing strip 21 and suitable lines of stitching, and the reinforcing strip 20 may include a 75 pocket for the reception of the stay 22. In a similar manner the sections of the left hand side member are connected to the back member by a reinforcing strip 23 and suitable 80 lines of stitching, while the sections 18 and 19 of this side member are connected to each other by a reinforcing strip 24 and suitable lines of stitching. Like the reinforcing strip 20 the reinforcing strip 23 85 may also include a pocket for the reception of the stay 25. These stays 22 and 25 extend from approximately the upper to the lower edges of the garment. The section 16 of the right hand side member is connected 90 to the section 12 of the front member by a reinforcing strip 26 and suitable lines of stitching. The free edge of the section 11 of the front member is provided with a reinforcing strip 27 on which in spaced positions there are secured a series of hooks 28. The free edge of the section 18 of the left hand side member is similarly provided with a reinforcing strip 29 in which in 95 spaced positions there is a series of eyes 30 corresponding in number with the hooks 28 so that each eye 30 is adapted to be engaged by a hook 28 for securing the garment in position on the body, it being understood that in the garment, as illustrated, 100 this connection is made at the left side and substantially also the axillary line of the body. Also, as illustrated, the back member in the lower portion thereof may be reinforced by a liner 31, which at its oppo- 110

site sides or edges is connected in the reinforcing strips 20 and 23 by the same lines of stitching which connect these reinforcing strips to the back and side members of the garment. At its upper edge this liner member 31 is not secured to the back member. As illustrated, the liner member will be provided with suitable stays 32 and 33.

In the front member there is a reinforcing member indicated at 34. This reinforcing member is preferably coextensive circumferentially with the central section 10 of the front member and at its opposite edges is secured in place by being connected to the reinforcing strips 13 and 14 by the same lines of stitching which through these reinforcing strips connect the central section 10 to the lateral sections 11 and 12. In this reinforcing member 34 I employ suitably spaced stays, as indicated respectively at 35, 36 and 37. The reinforcing member 34 preferably extends from its upper edge, which is adapted to lie at approximately the waist line, to its bottom edge 38, appreciably distant from the lower edge of the garment, this member being sufficiently long to overlie the abdomen of the wearer and to function as a support therefor.

In the front member of the garment I employ a diaphragm belt or strap. As illustrated this strap includes a central member of inelastic material and end members of elastic material. The central member, as shown, includes sections 39 and 40, the elastic end members being indicated at 41 and 42. The forward end of the elastic member 41 is connected to the outer edge of the section 39 by lines of stitching 43. Similarly the forward end of the member 42 is connected to the outer edge of the section 40 by lines of stitching 44. The sections 39 and 40 may be connected along a centrally disposed line by means of a reinforcing strip 45 and suitable lines of stitching, associated with which I may employ a stay 46. The sections 39 and 40 may also be fitted with stays as indicated at 47 and 48. The distant ends of the elastic members 41 and 42 are secured in the garment by being connected respectively to the reinforcing strip 27 and the reinforcing strip 26 by the same lines of stitching that connect the reinforcing strip 27 to the sections 11 and that connect the reinforcing strip 26 to the sections 12 and 16. This diaphragm belt or strap is placed in such a position that normally its upper edge is substantially coincident with the upper edge of the section 34. It is to be noted that the central inelastic member of the diaphragm strap or belt is wider in its central than in its end portions, both the upper and lower edges thereof converging toward the elastic members 41 and 42. The diaphragm strap or belt is not connected to the garment otherwise than de-

scribed so that except at its ends this diaphragm strap or belt may be shifted to position within certain limits for use. Furthermore, it will be noted that the length of the central member of this diaphragm belt 70 or strap is slightly greater than the width of the central section 10 of the front member, and that normally the length of the diaphragm strap or belt is appreciably less than the width of the front member whereby 75 in securing a garment in position on the body the strap or belt is extended to the width of the front member to exert a tension against the diaphragm to flatten or otherwise control the same. 80

As is customary the garment includes the usual hose supporters 49 and 50 depending from the front member, and 51 and 52 depending from the back member. The garment may also include the usual shoulder 85 straps, as indicated at 53 and 54 respectively.

I claim as my invention:

1. In a garment of the type described, a front member comprising a central section and lateral sections, a back member, side 90 members, the said members being connected and adapted to be secured on the body at the side thereof by connecting one edge of the front member to an adjacent edge of a side member, a reinforcing member extending 95 only across the central section of the front member and extending downwardly from approximately the waist line sufficiently far to overlie the abdomen, a diaphragm belt including a central section of inelastic material, the upper edge of which is normally coincident with the upper edge of the said reinforcing member, the said central section of the diaphragm belt being substantially coextensive circumferentially with the said reinforcing member, and end members of elastic material, the forward edges of the end members of elastic material being connected to the distant edges of the said central section of the belt and the distant edges of the 100 said end members of elastic material being connected respectively at the distant edges of the lateral sections of the front member, the diaphragm belt being otherwise free in the garment whereby and by means of the elastic members the diaphragm belt is shiftable to position and adapted to create a tension and a corresponding pressure against the diaphragm to flatten and control the same. 110

2. In a garment of the type described, a 115 front member, a back member, side members, the said members being connected and adapted to be secured on the body at the side thereof, a reinforcing member extending circumferentially part way across the 120 said front member and extending longitudinally from approximately the waist line to a point below the abdomen, and a diaphragm belt including a central section of inelastic material, the upper edge of which is nor- 130

mally coincident with the upper edge of the said reinforcing member, the said central section of the diaphragm belt being substantially coextensive circumferentially 5 with the said reinforcing member, and end members of elastic material, the forward edges of which are connected to the distant edges of the said central section of the belt and the distant edges of the said elastic mem- 10 bers of the belt being connected respectively

at the edges of the said front member, the diaphragm belt being otherwise free in the garment whereby and by means of the elastic members the diaphragm belt is shiftable to position and adapted to create a tension 15 and a corresponding pressure against the diaphragm to flatten and control the same.

Signed by me this 7th day of January, 1928.

WALDEMAR KOPS.
